UNITED STATES PATENT OFFICE.

DAVID FETTERS, OF BALTIMORE, MARYLAND.

GLASS-FURNACE.

SPECIFICATION forming part of Letters Patent No. 319,688, dated June 9, 1885.

Application filed February 13, 1885. (No model.)

To all whom it may concern:

Be it known that I, DAVID FETTERS, of Baltimore city, Maryland, have invented certain new and useful Improvements in Glass-Furnaces, of which the following is a specification, reference being had to the accompanying drawings, forming part hereof, in which—

Figure 1 is a transverse section of a glass-furnace constructed in accordance with my invention. Fig. 2 is a vertical section from front to rear of the same; and Fig. 3 is a horizontal section thereof, the floor being shown in plan view.

Like letters of reference mark the same parts in all the figures.

My invention has for its object to improve glass-furnaces by means of the construction, arrangement, and combination of parts which I shall now proceed to describe, and afterward specifically point out in the claims.

Referring to the drawings by letter, A is the front wall, B B' the side walls, and C the rear wall, of a glass-furnace. The front wall is open at a, to afford communication with the fire-box D, which is provided with grate D' and ash-chamber D''. The furnace has a vent or smoke pipe, a', and an opening, a'', in the bottom. The top of the furnace is arched from front to rear, as at A'. The sides B B' are respectively at right angles and inclined toward the front and rear, and are also inclined inward toward the top, as at B'' in Fig. 2.

E is the plate or bench supporting the four pots F F' F'' F'', which plate is divided from front to rear, and is shaped on its outer sides to correspond with the sides of the furnace against which it fits.

G G' are work-holes through which the glass is worked, which are located in upper half, B'', of the sides B B', the holes G G' being located in the parts B of the sides, and the holes G' G'' in the parts B'.

h is the floor surrounding the furnace, and which is provided with swingways or alleys H H' H'' H''' to correspond, relatively, with the pots and work-holes. By reason of the rear sections, B', of the sides of the furnace being inclined, or at other than a right angle, being an obtuse angle to the sections B B' of the sides and the rear C, the swing-

ways H' H'', in order to project at a right angle to the hole, are outwardly inclined from instead of being parallel with the swingways H H, as seen in Fig. 3. This allows more room between the ways and facilitates the work by allowing the blower to use a longer crane. The arrangement of the side walls allows the rear pots to be placed nearer together, insuring compactness and more thorough heating.

Having thus described my invention, what I claim, and desire to secure by Letters Patent, is—

1. A four-pot furnace having its sides divided near their center, forming straight sections B B', the latter of which is inclined to the former, the upper sections of each being inwardly inclined, and the front and rear walls being arched, as set forth.

2. A four-pot furnace having its sides divided near their center, forming straight sections B B', the latter of which is inclined to the former, the upper sections of each being inwardly inclined, and the front and rear walls being arched, and the furnace being provided with a pot-supporting plate made in two side sections, the rear half of each of which is carried nearer to the center, leaving a wider central opening in the front than in the rear, as set forth.

3. A four-pot furnace having its sides divided near their center, forming straight sections B B', the latter of which is inclined to the former, the upper sections of each being inwardly inclined, and the front and rear walls being arched, and the furnace being provided with a pot-supporting plate made in two side sections, the rear half of each of which is carried nearer to the center, leaving a wider central opening in the front than in the rear, each of the sections B B' being provided with a work-hole and swingway, those of the sections B' being inclined to those of sections B, as set forth.

In testimony whereof I have hereunto set my hand in the presence of two witnesses.

DAVID FETTERS.

Witnesses:

S. BRASHEARS,
J. MASON GOSZLER.
